UNITED STATES PATENT OFFICE.

OLIVER M. KING AND ANDREW J. BROOKS, OF ST. JOSEPH, MISSOURI, ASSIGNEES, BY
DIRECT AND MESNE ASSIGNMENTS, TO THE STANDARD OIL COMPANY, A COR-
PORATION OF INDIANA.

AIR-HOSE PROTECTOR.

Application filed March 10, 1919. Serial No. 281,893.

To all whom it may concern:

Be it known that we, OLIVER M. KING and ANDREW J. BROOKS, citizens of the United States, residing at St. Joseph, in the county of Buchanan and State of Missouri, have invented certain new and useful Improvements in Air-Hose Protectors; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to air hose storage devices, and more particularly to a device for protecting the hose from which automobileists refill their tires at gasoline service stations, the present invention comprising an improvement, in detail construction, of the device forming the subject matter of the co-pending application of Andrew J. Brooks, Serial No. 456,919.

In the accompanying drawings, forming part of this application:

Fig. 1 is an elevational view of a device embodying our invention in the form of a lamp post, the upper and lower portions of the post being broken away to disclose the contained structure.

Fig. 2 is a detail, vertical, sectional view of the post, disclosing the contained parts viewed from a different angle.

Fig. 3 is a horizontal section of the supporting standard showing the fixed pulley bracket and pulley.

1 designates a hollow column having an enlarged base portion 2 and a cap member 40 which may consist of a translucent globe or similar element 3 upon which may be stamped, embossed or otherwise associated, suitable lettering as, for example, the word "Air" or "Free air" and within the globe 3 45 may preferably be arranged a source of light. The bottom of the base 2 is provided with a base plate 4 having an opening 5 to receive the lower end of the hollow standard 6 which may consist of a suitable pipe extending substantially the entire length of the casing or column 1 and projecting into the dome or globe 3.

The retracting mechanism is shown as being supported by the standard or pipe 6

and at the lower end of the standard 6 is a pulley bracket 7 comprising a jaw 8 carrying a guard plate 9 in which is mounted a pulley 10, the guard plate also being provided with an outwardly projecting flange 11 to which certain guide rods are attached, as will be explained hereinafter. The jaw 8 is fastened about the standard 6 by a clevis 12, the free ends of which extend through the projections 13 and 14 of the bracket 7, the clevis and jaw being secured by the fastening devices 15 and 16. Near the top of the standard 6 is a bracket 17 likewise fastened to the standard by a clevis 18 and the bracket 17 is provided with a guard member 19 in which is journaled a pulley 20 over which passes a flexible cable 21, to one end of which is attached a counter-balance weight 22 vertically guidable in the hollow standard 6, the other end of the cable 21 being fastened to a pulley sheave 23 carrying the pulley 24 and having an outwardly projecting flange 25 with openings therein through which the guide rods 26 and 27 project. The guide rods are fastened to the flange 11 and to the eye bolts 28 and 29 carried by the plate 30 supported on the bracket 17 and these guide rods are so spaced from the standard 6 that the pulley 24 will be properly guided in its vertical longitudinal movement toward and away from the bottom of the casing or column 1. The standard 6 may be fastened near its upper end to the interior of the casing 1 by any suitable means as, for example, a bracket 31. Adjacent to the standard 6 is a vertical conduit 32 which extends above the same and which carries a lamp socket 33 for an incandescent lamp 34 whereby the dome or globe 3 may be illuminated.

35 is an air inlet pipe to which the hose 36 is attached, said hose passing over the pulley 24 in the sheave 23 and around the pulley 10 in the sheave or guard 9, the free end of the hose 36 passing through an opening 37 in the base of the column 1, the opening being provided with an anti-friction device. The anti-friction device consists of a frame 37' provided with a plurality of concave rollers 38 arranged about a common center, the concave portion of each roller representing substantially a quarter of a circle so that when the rollers are assembled, a hose opening will be provided,

surrounded by rolling walls so that the hose may be projected or retracted through the opening 37 without friction. The end of the hose is provided with a ball or collar 39 adjacent to the valve 40 so that when the operator releases the hose, the ball or collar 39 will contact with the edge 41 to limit the retractive movement of the hose within the column 1. For the purpose of safety, 5 we provide a removable door or closure on the base 2 which may fit over the valve and the ball or collar and close the opening 37, the door being adapted to be secured in any manner, as, for example, with a hasp and 10 lock, the means of closing being non-essential as the purpose is to protect the valve 40 from being tampered with by unauthorized persons during the night or during inactive hours. 15 When the parts are assembled and the operator desires to utilize air for the purpose of inflating tires or for other causes, the nozzle 40 may be grasped and a pull will permit the pulley 24 to be pulled down in 20 opposition to the counter-balance weight 22 so that the pulley 24 will approach the pulley 10 and thereby permit a sufficient length of hose to be pulled through the opening 37 to allow the operator to reach the car to inflate the tires thereof. As soon as the operator releases the nozzle 40, the counter-balance weight 22 will drop toward the bottom 25 of the standard 6, raising the pulley 24 and thereby retracting the hose 36 within the column 1. The counter-balance weight and the pulley 24 will always have a normal tendency to retain the hose retracted within the column where it will be protected against moisture, danger of being cut or other rough 30 treatment so that the only time the hose will be exposed will be when it is being legitimately used for conveying air to serve some useful purpose. Thus, it will be apparent that the life of the hose will be materially 35 prolonged, that the hose will be kept clean and that the nozzle 40 will always be in an accessible position. 40 The column 1 may partake of any configuration adapted to serve the purpose intended and therefore, we do not wish to be limited to any particular design although 45

the device is susceptible to many modifications particularly as to the exterior appearance without departing from the spirit of the invention. For example, if desired, a plain casing or column may be utilized so that the same may be sunk into the ground with the opening near the top so that the hose will be accessible therethrough. Ordinarily, however, we prefer to arrange the entire device upon the surface of the ground and encase the same in a more or less artistic casing or column and generally in such manner that the casing not only serves as a protection for the hose but also may be provided with a dome or globe adapted to serve the dual purpose of a sign and an illuminating device. 55 60 65 70

Having thus described our invention, what we claim as new therein and desire to secure by Letters-Patent is:—

1. A device of the character described, comprising a hollow standard, a plate carried by the standard, guides connected to the plate, a pulley having fixed mounting on the plate, a pulley casing controlled by said guides, a hose pulley rotatable in the casing, a weight in the standard, a cable passing over the fixedly mounted pulley and connecting the weight and hose pulley casing, 75 an inlet pipe, and a hose connected with the inlet pipe and run over the hose pulley. 80

2. A device of the character described, comprising a hollow standard, a plate carried by the standard, guides connected to the plate, a pulley having fixed mounting on the plate, a casing controlled by said guides, a hose pulley rotatable in the casing, a weight in the standard, a flexible connection passing over the fixedly mounted pulley and attached 85 to the weight and to the hose pulley casing at opposite sides of the fixedly mounted pulley, a pulley secured to said standard adjacent the bottom thereof complementary to the hose pulley but fixed with respect to the standard, an inlet pipe, and a hose connected with the inlet pipe and run over the complementary hose pulleys. 90 95

In testimony whereof we affix our signatures.

OLIVER M. KING.
ANDREW J. BROOKS.
